FINGER RING

Thomas C. Katke, Wauwatosa, Wis., assignor to
Milwaukee Board of School Directors, Milwaukee, Wis., a municipal body of Wisconsin

Application April 14, 1950, Serial No. 9,227

Term of patent 14 years

(Cl. D45—10)

To all whom it may concern:

Be it known that I, Thomas C. Katke, a citizen of the United States, residing at Wauwatosa, in the county of Milwaukee and State of Wisconsin, have invented a new, original, and ornamental Design for a Finger Ring, of which the following is a specification, reference being had to the accompanying drawing, forming a part thereof, and in which:

Figure 1 is a side elevation of a finger ring embodying my new design, and

Figure 2 is an elevational view of the opposite side thereof.

Figure 3 is an edge view of the finger ring, and
Figure 4 is a top plan view thereof.

I claim:

The ornamental design for a finger ring, as shown.

THOMAS C. KATKE.
